UNITED STATES PATENT OFFICE.

EDWIN F. PORTER, OF BOSTON, MASSACHUSETTS, ASSIGNOR TO THE BAY STATE ELECTRIC HEAT & LIGHT COMPANY, OF JERSEY CITY, NEW JERSEY.

APPARATUS FOR HEATING AND AGITATING AIR.

SPECIFICATION forming part of Letters Patent No. 684,458, dated October 15, 1901.

Application filed December 6, 1897. Serial No. 680,957. (No model.)

To all whom it may concern:

Be it known that I, EDWIN F. PORTER, a subject of the Queen of Great Britain, residing at Boston, in the county of Suffolk and State of Massachusetts, have invented certain new and useful Improvements in Apparatus for Heating and Agitating Air, of which the following is a specification.

My invention relates to improvements in apparatus for heating and agitating air; and its object is to thoroughly heat and distribute a body of air throughout an apartment.

In carrying out my invention I use a fan, preferably in combination with a hood, which brings heated air and products of combustion in contact with blades, from which it is thrown into the apartment, the air being first heated by oil or gas jets placed below the hood. By means of this device a large body of air is more rapidly and thoroughly heated and diffused throughout an apartment than is possible with any present style of stationary gas-radiator or gas-log, which imparts its heat to the air coming in contact therewith by ordinary slow circulation.

My invention consists of certain novel features hereinafter described, and particularly pointed out in the claims.

In the accompanying drawings, which illustrate a construction embodying my invention, Figure 1 is a side elevation, partly broken away to show the gas or oil jets. Fig. 2 is a front elevation. Fig. 3 is a rear view with the hood partly broken away and showing the fan and motor for running the fan. Fig. 4 is a side view in section, showing the construction of the motor.

Like letters of reference refer to like parts throughout the several views.

To a suitable base A there is secured a hood B; and in the bottom of said hood there is arranged a series of oil or gas jets C, which heat the air entering through the openings C' in the hood B. Through an opening D in the hood B the shaft E passes and is operated by means of a suitable motor F, resting on the support G. On the front end of said shaft E there is arranged a fan H, fast on the shaft E and having a series of blades H'. The air enters at the apertures C' and, being heated by

the burner, rises and circulates against the fan H, which fan, being revolved by the motor F, throws the heated air and products of combustion off into the apartment and by its exhaust action accelerates the draft through 55 the apertures C', thereby heating a greater amount of air than would be heated by the ordinary circulation, as is the case with the present style of gas-radiators.

In Figs. 3 and 4 is shown a specially-designed motor for operating the fan, and this motor consists of an expansion-chamber K, inclosing a displacer L, which is a solid cylinder of any desirable material and is operated by the lever M, working in the slot M' 60 in the displacer L, and the lever M in turn is operated by the link N, pivoted to the piston O, which operates in the cylinder P. The motion from the piston O is imparted to the fan H through the piston-rod Q, connected to 65 the crank R on the shaft S, which is supported by the beams T. The shaft continues through the hood B, and to it is secured the fan H, which is revolved by the rise and fall of the piston O. The to-and-fro movement 70 of the lever M, pivoted at M', is caused by the contact at the upper end of the lever M of the nuts M³ and M⁴. The expansion-chamber K extends into the hood B and is heated by the burner C, thereby in this device utilizing the heating-flame for running 75 the motor and for heating the room. The body of air K', being first heated in the end of the chamber K, located over the burner C, is forced by the movement of the displacer L, 80 owing to the expansion of air in the chamber K, against the under side of the piston O into the opposite or cool end of the chamber K, (shown in Fig. 4,) where it contracts, causing atmospheric pressure to depress the piston O, 85 and the piston O descending forces the lever M backward, throwing the displacer L to the outer end of the chamber K, which forces the body of air K' to the inner end of the chamber K through the space around the displacer 90 L, which works loosely in the chamber K on the ball-bearings K². The body of air K' being now in the inner heated end of the chamber K is expanded, forcing the piston O upward, thereby completing the revolution of 95 100

the shaft S by the movement of the piston O, and this motion is repeated while the burner C is in operation. In this arrangement, as in Figs. 1 and 2, the air entering the hood B is heated and rises and is distributed with the products of combustion throughout the room by the motion of the fan H.

In apparatuses where the fan or equivalent device is operated solely by the current of heated air and products of combustion the force of the current and the force of the motor are the same, and in practice the operation of the motor by such current would be retarded owing to the friction of the parts, for the apparatus to be effective and to produce a lateral diffusion of the heated air and products of combustion the motor operating the fan must have a greater potential than the draft or ascending current of heated air and products of combustion in order that the current of heated air and products of combustion may be accelerated and rapidly diffused throughout the apartment.

I do not limit myself to the arrangement and construction shown, as the same may be varied without departing from the spirit of my invention.

Having thus ascertained the nature of my invention and set forth a construction embodying the same, what I claim as new, and desire to secure by Letters Patent of the United States, is—

1. In an apparatus of the character specified, a source of heat for heating the air by direct contact, a fan exposed to the surrounding air for agitating the same by the direct contact of its blades therewith and for diffusing the heated air and products of combustion

tion, a hood in which is located said source of heat and having perforations to admit air and adapted to convey the heated air and products of combustion to the fan, and a motor actuated independently of the draft of said heated air and products of combustion for operating said fan.

2. In an apparatus of the class described, gas or oil burners for heating the air by direct contact, a fan exposed to the surrounding air for agitating the same by direct contact of its blades therewith and for diffusing the heated air and products of combustion produced by the burners, a motor for operating said fan, and a source of energy for driving said motor separate and distinct from said burners.

3. In an apparatus of the class described, gas or oil burners for heating the air by direct contact, a fan exposed to the surrounding air for agitating the same by the direct contact of its blades therewith and for diffusing the heated air and products of combustion from said burners, a hood for conveying the heated air and products of combustion from said burners to said fan, a motor for operating said fan, and a source of energy separate and distinct from said burners for driving said motor.

In witness whereof I have signed my name to this specification, in the presence of two subscribing witnesses, this 1st day of December, A. D. 1897.

EDWIN F. PORTER.
